(57) **CLAIM**

I claim the ornamental design for the dresser mirror, as shown and described.

DESCRIPTION

FIG. 1 is a front elevational view of a dresser mirror showing my new design;

FIG. 2 is left-side elevational view thereof;

FIG. 3 is right-side elevational view thereof; and,

FIG. 4 is a top plan view thereof.

The claimed design does not include any specific depth for the specific ornamental details shown within the perimeter moldings.
